(57) **CLAIM**

The ornamental design for an elevated wheelchair, as shown and described.

DESCRIPTION

FIG. 1 is a front, top, left perspective view of an elevated wheelchair showing our new design and in the raised position;

FIG. 2 is a rear, top, right perspective view of the elevated wheelchair shown in FIG. 1;

FIG. 3 a front elevational view of the elevated wheelchair shown in FIG. 1;

FIG. 4 is a rear elevational view of the elevated wheelchair shown in FIG. 1;

FIG. 5 is a right-side elevational view of the elevated wheelchair shown in FIG. 1;

FIG. 6 is a left-side elevational view of the elevated wheelchair shown in FIG. 1;

FIG. 7 is a top plan view of the elevated wheelchair shown in FIG. 1; and,

FIG. 8 is a bottom plan view of the elevated wheelchair shown in FIG. 1.

The dash-dot-dash broken lines represent an optional stitching pattern and the broken lines immediately adjacent the shaded areas without adjacent shading on both sides of the broken line represent the bounds of the claimed design. All other broken lines are directed to environment and are for illustrative purposes only; the broken lines form no part of the claimed design.
